United States Patent Office

Des. 204,589
Patented May 3, 1966

204,589

ADVERTISING SIGN

Herbert W. Truitt, 452 8th Ave., San Diego, Calif.

Filed July 26, 1965, Ser. No. 86,315

Term of patent 14 years

(Cl. D1—12)

I claim:

The ornamental design for an advertising sign, substantially as shown and described.
